UNITED STATES PATENT OFFICE.

BENJAMIN F. KETCHAM, OF PORT JERVIS, NEW YORK.

PILLOW-SHAM HOLDER.

SPECIFICATION forming part of Letters Patent No. 247,831, dated October 4, 1881.

Application filed March 9, 1881. (No model.)

To all whom it may concern:

Be it known that I, BENJAMIN F. KETCHAM, a citizen of the United States, residing at Port Jervis, in the county of Orange and State of New York, have invented certain new and useful Improvements in Pillow-Sham Holders; and I do hereby declare that the following is a full, clear, and exact description of the same, reference being had to the annexed drawings, making a part of this specification, and to the letters and figures of reference marked thereon.

Figure 1 of the drawings represents a perspective view of my invention, and Fig. 2 a cross-section thereof.

15 The present invention has relation to certain new and useful improvements in that class of devices adapted to be attached to the head-board of a bedstead for holding the pillow-shams over the pillows or off of the same, as 20 circumstances may require.

The invention consists in the several details of construction, as hereinafter described, and subsequently pointed out in the claim.

In the accompanying drawings, A represents 25 the frame, of any desirable length, provided with means for attaching it to the head-board of the bedstead. To the end brackets, a b, of the frame A is journaled a roller, B, to which is connected spring-arms c, projecting at right 30 angles to the axis of said roller. The roller B, at one of its ends, has a notch, d, for engaging a pawl, e, projecting from a lever, C. This pawl e is kept engaged with the notch d by spring f, one end of which is secured to the

back of the lever and the other end bearing 35 against a pin, g, upon the inner side of the plate or bracket b. The pawl, engaging with the notch in the end of the roller, holds said roller in position and the arms c down upon the pillow-sham, and when it is desired to release 40 said arms and hold the pillow-shams off and away from the pillows, simply press on the lever C, which will release the pawl e from the notch d and admit of the roller B, with its arms c, being turned to bring said arms up against 45 the head-board.

If desired, the frame A may be entirely dispensed with and the brackets a b fastened by screws or other means directly to the head-board of the bedstead, and in some cases the 50 latter is preferable, and therefore I do not desire to confine myself to the frame A.

Having now fully described my invention, what I claim as new, and desire to secure by Letters Patent, is—

55 A pillow-sham holder consisting of the brackets a b and roller B, with notch d and arms e, in combination with the lever C, carrying pawl e, and the spring f, constructed to operate substantially as and for the purpose set forth. 60

In testimony that I claim the above I have hereunto subscribed my name in the presence of two witnesses.

BENJAMIN FRANKLIN KETCHAM.
